WITNESS:

W. B. Miller,
INVENTOR

BY *Victor J. Evans*

ATTORNEY

UNITED STATES PATENT OFFICE.

WILLIE BARTOE MILLER, OF LITTLE ROCK, ARKANSAS.

TRUNK STRAP.

Application filed April 30, 1924. Serial No. 710,086.

To all whom it may concern:

Be it known that I, WILLIE B. MILLER, a citizen of the United States, residing at Little Rock, in the county of Pulaski and State 5 of Arkansas, have invented new and useful Improvements in Trunk Straps, of which the following is a specification.

This invention relates to fastening means for trunks, boxes and the like, the general 10 object of the invention being to facilitate the placing of flexible members around the trunk and for easily and quickly fastening the loose ends of the members together.

Another object of the invention is to provide a novel form of buckle for connecting the loose ends of the flexible members to each other.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a view showing the invention in use.

Figure 2 is a view of the improved buckle.

In these views, the trunk or box is shown at A in dotted lines and the flexible members 35 are shown as ropes or cables 1 and straps 2, the ropes being arranged at the lower part of the trunk or box and the straps at the upper part thereof. The loose ends of the flexible members are connected together by 40 the buckles B, each of which is of substantially hour-glass shape with the bottom part being of V-shape, as shown at 3. A tongue 4 is connected with the bar 5 which connects the constricted central part of the device 45 together, the tongue engaging the top part

of the device in the usual manner. The tongues of the devices are arranged to engage holes formed in the straps while the cables or ropes are adapted to be tied to the V-shaped lower part of the devices, as clearly shown in Figure 1.

It will thus be seen that with this invention a trunk or box can be easily and quickly tied as it is simply necessary to place the trunk or box upon the ropes or cables and 55 then place the straps upon the trunk or box and fasten the ends of the straps to the ends of the ropes by the devices B.

It is thought from the foregoing description that the advantages and novel features 60 of my invention will be readily apparent.

I desire it to be understood that I may make changes in the construction and in the combination and arrangement of the several parts, provided that such changes fall within 65 the scope of the appended claims.

What I claim is:—

1. A fastener for a trunk or box comprising a longitudinally extending cable and transversely extending cables connected at 70 their centers with the longitudinally extending cables, a longitudinally extending strap and transversely arranged straps connected with the first strap and buckles for engaging the loose ends of the straps and adapted 75 to be tied to the loose ends of the cables, said buckle consisting of a member having a constricted central part, a bar connecting the sides of the constricted part together, a tongue pivoted to the bar for engaging a 80 strap and the lower part of the device being of V-shape to receive the rope end.

2. A buckle of the class described comprising a body of substantially hour-glass shape with its lower end of V-shape, a bar connecting the constricted central portion together and a tongue pivoted on said bar. 85

In testimony whereof I affix my signature.

WILLIE BARTOE MILLER.
